US00D864721S

(12) **United States Design Patent** (10) Patent No.: **US D864,721 S**
(45) Date of Patent: **** Oct. 29, 2019**

(54) **INSULATION FOR PACKAGING**

(71) Applicant: **MENZEL DIVERSIFIED ENTERPRISES, LLC**, Mooresville, NC (US)

(72) Inventors: **Robert W. Menzel, Jr.**, Mooresville, NC (US); **David Kevin Vance**, Concord, NC (US)

(73) Assignee: **MENZEL DIVERSIFIED ENTERPRISES, LLC**, Mooresville, NC (US)

(**) Term: **15 Years**

(21) Appl. No.: **35/001,475**

(22) Filed: **Dec. 22, 2017**

(80) **Hague Agreement Data**

Int. Filing Date: **Dec. 22, 2017**

Int. Reg. No.: **DM/099523**

Int. Reg. Date: **Dec. 22, 2017**

Int. Reg. Pub. Date: **Jun. 22, 2018**

(51) **LOC (12) Cl.** **09-07**

(52) **U.S. Cl.**

USPC **D9/456**

(58) **Field of Classification Search**

USPC **D9/456**

CPC B65D 81/05; B65D 81/107; B65B 1/04
